STATION SELECTOR

Alfred H. Turner, Collingswood, N. J., assignor to
 Radio Corporation of America, a corporation of
 Delaware

Application January 14, 1938, Serial No. 184,913

10 Claims. (Cl. 178—44)

My invention relates to station selectors or tuning devices and particularly to tuning means for television receivers or the like.

In television receivers, it has previously been the practice to utilize station selecting means similar to that usually employed in broadcast receivers, namely, a tunable circuit comprising an inductance coil of fixed inductance value and a variable condenser connected across it for tuning to the desired station. A station selecting circuit of this type has several disadvantages when employed in a receiver designed for the high frequencies employed in television transmission.

For example, in such a circuit, because of minimum circuit capacity, the inductance is necessarily small in order that the tunable circuit will resonate at the high frequency end of the tuning range. This small inductance, in turn, means very low impedance for two such circuits coupled and loaded to pass the desired 6 megacycle band. The net result is a very low voltage gain from the antenna to the first detector.

Since plate hiss in the first detector, if it is not exceeded by outside interference, is the limiting disturbance in the video channel of a television receiver, any improvement in gain up to the first detector results in a proportionate improvement in signal-to-hiss ratio.

It is accordingly an object of my invention to provide an improved television receiver.

A further object of my invention is to improve the signal-to-hiss ratio in a television receiver.

A still further object of my invention is to provide an improved station selector or tuning means for high frequency radio receivers such as television receivers.

A still further object of my invention is to provide an improved variable inductance tuning device for short wave radio receivers.

In the preferred embodiment of my invention an inductance tuning device is provided with a plurality of tapped inductance coils for the radio frequency selecting circuit and for the oscillator of a superheterodyne receiver. The coils are mounted coaxially on a gang switch of the type having a plurality of "wafers" carrying contact points, one coil being located adjacent to each wafer whereby very short leads may be run from the coil taps to the switch contact points.

The tuning device preferably comprises two tuned circuits which are so capacitively coupled as to provide a band pass filter. By employing capacity coupling and tapped inductance coils the filter is made to have a pass band which remains

substantially constant over the entire tuning range of the receiver.

The impedance of the receiver input is made to match the impedance of the antenna transmission line over the entire tuning range of the receiver by properly locating the transmission line coupling coil with respect to the tapped coil of the first tuned circuit whereby the inductance of the coupling coil is reduced in value as the receiver is tuned to higher frequencies.

The invention will be better understood from the following description taken in connection with the accompanying drawing in which

Figure 1 is a circuit diagram of a portion of a television receiver embodying my invention.

Figure 2 is a plan view of the station selecting unit drawn approximately to full scale, which is utilized in the receiver shown in Fig. 1.

Figure 3 is a view on the line 3—3 in Fig. 2 looking in the direction of the arrows.

Figure 4 is a schematic diagram which is referred to in explaining the invention.

Figure 5 is a view illustrating a modification of my invention, and

Figure 6 is a circuit diagram of another embodiment of my invention.

Referring to Fig. 1, the receiver comprises a pair of coupled tuned circuits 2 and 3 which function as a bandpass filter for coupling the antenna, such as a dipole 4, to the first detector tube 6 of the receiver which preferably is of the superheterodyne type.

The tuned circuit 2 comprises a tapped inductance coil 7 and a fixed condenser 8 which is effectively in parallel therewith.

The tuned circuit 3 comprises a tapped inductance coil 9 which has effectively in parallel therewith the input capacity of the first detector tube 6, this capacity being indicated at 11.

The circuits 2 and 3 are coupled through a condenser 12 which is common to the two tuned circuits, this being substantially the only coupling between the circuits. This series capacitive coupling is preferred, although parallel capacitive coupling may be used by connecting a very small condenser between the upper ends of coils 7 and 9 as will be described in connection with Fig. 6.

It will be seen that the tuned primary circuit 2 may be traced from ground through coupling condenser 12, through primary coil 7 and the condenser 8 back to ground. The tuned secondary circuit 3 may be traced from ground through coupling condenser 12, through the secondary coil 9 and the tube input capacity 11 back to ground. The primary and secondary circuits are each

tuned approximately to the same frequency and the coupling between circuits is of the correct value to give the two coupled circuits a bandpass characteristic.

- 5 The effective inductance of each of the coils 7 and 9 may be varied by shorting a certain number of turns in each coil. To accomplish this, coil 7 is tapped at a plurality of points and connections made to switch contact points 13 10 through short leads 15. A switch arm 14 makes a coil shorting connection between the lower end of the coil 7 and selected contact points 13. While it is preferred to short the unused coil turns, this is not necessary in all cases.
- 15 Similarly, the coil 9 is tapped at a plurality of points which are connected to switch contact points 16. A switch arm 17 which is connected to the lower end of the coil 9 shorts a certain number of turns, the number depending upon 20 the position of the switch arm.

It may be noted at this point that it would be expected that capacity coupling between two inductively tuned circuits would give a constant percentage pass band width over the tuning 25 range, the actual band width varying over the tuning range. For equal width of television channels it is very desirable that the band width of the selecting circuit be substantially the same at all points in the tuning range. In my selecting 30 circuit this desirable result is obtained since the combination of capacity coupling and tapped inductance coils results in a variation of distributed capacity across the coils as the circuit is tuned which tends to keep the band width constant. 35 This feature will be discussed in more detail hereinafter.

The antenna 4 is coupled to the coil 7 through a coupling coil 18, the coils 7 and 18 being inductively coupled. Preferably, the antenna is connected to coil 18 through a transmission line 19, the mid-point of coil 18 being connected to ground.

As will be explained at another point in this specification, the coupling coil 18 is so located 45 on the coil 7 with respect to the turns which are shorted by the switch 14 that the receiver input impedance (the impedance at the terminals of coil 18) remains substantially constant over the entire tuning range of the receiver. Because of 50 this, it is not necessary to provide any taps and associated switch for the coil 18 to keep the receiver input impedance matched to the transmission line impedance.

For the purpose of making the tuned circuits 55 2 and 3 symmetrical, a coil 21 is wound adjacent to the coil 9 and its center point is grounded. This is a simple way of making the capacities of the two circuits substantially the same.

The detector tube 6 may be of any suitable 60 type such as the pentode illustrated having an indirectly heated cathode 22, a control grid 23, a screen grid 24, a suppressor grid 26 and a plate 27. The control grid 23 may be biased slightly negative by means of a self-bias resistor 28 which 65 is by-passed by a condenser 29. The usual bypass condenser 31 is provided for the screen grid 24. The bias is applied to the grid 23 through a resistor 20 connected between ground and the tap 15a of the coil 7. Resistor 20 also provides 70 the necessary loading for circuit 2.

The tunable oscillator 30 of the superheterodyne receiver includes a vacuum tube 32 which may be of the three-element type having an indirectly heated cathode 33, a control grid 34 and a plate 75 36. This oscillator produces oscillations 10 mega-

cycles higher than the carrier frequency of the incoming signal.

In the specific example illustrated, the oscillator 30 has a tunable plate circuit comprising a tapped inductance coil 37 which is coupled to a coil 38 in the grid circuit. In the grid circuit there preferably is the usual grid condenser 39 and grid leak resistor 41. A positive operating voltage is supplied to the plate 36 through a filter resistor 42 and the coil 37.

10 The tuning capacity across the coil 37 is provided by the output capacity of the tube 32 indicated at 43 and by the trimmer condenser 44 in parallel with capacity 43. The capacities 43 and 44 are connected across the coil 37 through a condenser 46.

The tuning of the oscillator is accomplished (except for fine adjustments by condenser 44) by means of a switch 47 which makes contact with one of the switch contact points 48 to short out sections of the coil 37.

The coupling of the oscillator 30 to the first detector 6 may be through a coupling condenser 49.

The short-circuiting switches 14, 17 and 47 for 25 the tuned circuits 2 and 3 and for the oscillator, respectively, are ganged whereby the receiver may be tuned by a single knob.

In Fig. 2 there is shown the mechanical structure by means of which I obtain satisfactory operation with the above-described circuit at the high frequencies involved in television transmission and reception. In Figs. 1 and 2 like parts are indicated by the same reference numerals.

30 Referring to Fig. 2, the several inductance coils are mounted coaxially with a gang switch of well-known construction. The switch comprises a plate 51 which is suitably attached, as by a press fit, to a bushing 52. The bushing 52 is threaded on the outside and provided with a nut 53 and washer 54 for mounting the switch on an upwardly projecting flange 56 of a metal base 57.

A hollow tube shaft 58 having a shoulder 59 extends through the bushing 52, this tube shaft having mounted thereon the switch arms 14, 17 and 47. A knob 50 is attached to the end of shaft 58 for rotating it and the switch arms.

In order to hold the shaft 58 snugly in the bushing 52 and in order to make the switch arms snap into engagement with successive contact points as the knob 50 is rotated, an arm 61 is welded or otherwise attached to the shaft 58 and a ring 62 of spring steel or the like is attached to the ends of the arm 61. Two diametrically opposed balls 63 are held between the spring ring 55 62 and the plate 51 whereby the shoulder 59 is held against the bushing 52.

The plate 51 has formed thereon in a circle a plurality of raised portions 64, one for each switch contact point. As the knob 50 is rotated, the balls 63 ride up over two diametrically opposed projections 64 and then snap into the next switch position.

The three switches 13-14, 16-17 and 48-47 65 are of similar construction. This construction will be understood from the following description of switch 13-14 with reference to Figs. 2 and 3.

The switch contact points 13 are attached to 70 a "wafer" 66 of insulating material, this wafer being supported by rods 67 and 68 which are bolted to the plate 51.

The switch arm 14 is attached to a disk 69 of insulating material such as fibre. The disc 69 is forced onto a flattened section of the shaft 58.

whereby the disc 69 and arm 14 are rotated when shaft 58 is rotated. The switch arm 14 is electrically connected to or is an integral part of a ring 71 whereby there is always electrical contact between the arm 14 and a brush 72 riding on the ring.

In a similar way, the switch arms 17 and 47 are always in electrical contact with the brushes connected to terminals 73 and 74, respectively.

10 Each of the coils 7, 9 and 37 preferably is wound on a grooved or threaded fibre tube. Each coil is supported by means of the heavy leads connecting the tapped points on the coil to the switch contact points. For example, the coil 7 is supported by the leads 15.

15 The trimmer condenser 44 comprises a fixed plate 44a supported by the fibre tube 37a upon which coil 37 is wound and a rotatable plate 44b attached to a shaft 76. The shaft 76 extends through the hollow shaft 58 and may be rotated by means of a knob 77 for adjusting condenser 44.

20 The windings 18, 21 and 38 are of fine wire wound between the turns of heavier wire forming the coils 7, 9 and 37, respectively, as shown in Fig. 2. The location of the coil 18 with respect to the coil 7 is important for best results. By properly locating the coil 18, its inductance is made to decrease as the receiver is tuned to higher frequencies (that is, as an increasing number of coil turns are shorted) whereby the receiver input impedance is matched to the transmission line impedance for all station settings. It will be noted that the turns ratio of coils 18 and 7 changes as the receiver station is tuned and that the obvious way to keep the receiver and transmission line impedances matched is to switch out part of the coil 18 simultaneously with switching of the coil 7 to keep the said turns ratio constant. This 25 would complicate the switching, especially since the transmission line should be kept balanced with respect to ground.

25 I have found that by locating the coil 18 (which in the example illustrated is only one and one-third turns) adjacent to the last tap on coil 7 with part of coil 18 inside the short-circuited turns and part of it outside the short-circuited turns when switch 14 is on the last tap, the impedance of coil 18 is controlled in the desired 30 manner as the receiver is tuned. By the "last tap" is meant the last tap at the high frequency end of coil 7, that is, the tap indicated at 15a nearest the condenser 8. It will be noted that a small number of taps has been indicated in Fig. 1 35 in order to simplify the drawing, tap 15a being the eleventh tap in the actual structure as indicated in Fig. 4.

35 With this arrangement, as more and more turns of coil 7 are shorted, the shorted turns 40 act on coil 18 to reduce its inductance an increasing amount. It has been found that the preferred relation of coils is to have the mid-tap 15a of coil 18 located near the last tap 15a of coil 7 as shown in Fig. 2.

45 It will be noted that the relation of coil 21 to coil 9 is the same as the relation of coil 18 to coil 7 whereby the tuned circuits 2 and 3 are balanced or symmetrical.

50 In the oscillator, the grid coil 38, which has two turns, should be so located with respect to the coil 37 that its inductance is substantially reduced by the shorted turns of coil 37 as the receiver is tuned to the higher frequencies. This 55 action in the oscillator circuit is necessary for best operation since, at the highest frequency

setting, the grid coil 38 has more effective turns than the plate coil 37 and the grid circuit will resonate to control the frequency unless the grid circuit inductance is substantially reduced.

5 As shown in Fig. 2, the coil 38 is located substantially within the short-circuited turns of coil 37 when the receiver is tuned to the highest frequency. To accentuate the reduction in the inductance of coil 38 by the short-circuited turns, the two turns of coil 38 are spaced apart by one 10 unused turn space.

10 As previously mentioned, my station selector is so designed that the pass band stays substantially constant over the entire tuning range of the receiver. By utilizing the combination of capac- 15 ity coupling and tapped inductance coils, I cause the percentage coupling to be reduced as the receiver is tuned to the higher frequencies whereby the width of the pass band of the two coupled circuits remains substantially constant. As a 20 matter of fact, in some applications the band width will actually decrease as the receiver is tuned to higher frequencies.

15 The reason the width of the pass band remains as constant as is desired may be explained as 25 follows: The percentage coupling between circuits 2 and 3 (where the tuning capacities are equal) is the ratio of the tuning capacity of a coil to the capacity of coupling condenser 12. Considering coil 7, the tuning capacity is the 30 capacity of condenser 8 plus the distributed capacity of the effective portion of the coil. As switch arm 14 is moved from a lower tap towards the last tap 15a to tune the receiver to higher 35 frequencies, the distributed capacity across the unshorted section of coil 7 decreases. Thus, the tuning capacity decreases and the percentage coupling decreases, whereby the usual large increase in pass band width is avoided.

40 The resistor 20 is so connected that it also aids in keeping the pass band width approximately constant, although the distributed capacity is the main factor in obtaining this result. It will be noted that resistor 20 is connected between ground and a point on the coil 7 intermediate its ends whereby it is in shunt to some of the inductance of the tuned primary circuit 2 when the lower part of the coil is not shorted but not in shunt to the tuning inductance when the switch arm 14 is on the last tap 15a, i. e., 50 when the selector is tuned to the highest frequency. In this connection, it should be kept in mind that the coupling condenser 12 has a large capacity compared with the capacity of tuning condenser 8. 55

55 In some designs, it may be preferred to connect resistor 20 between ground and a point on the secondary coil 9. Whether the resistor is connected across the primary or the secondary, it may be preferred to connect it between ground 60 and a coil tap other than the one indicated on the drawing.

65 In order to make my station selector operate at the greatest efficiency for the very high frequencies involved in television transmission without resorting to coils of variable winding pitch and/or of variable coil diameter, it is so designed that the station settings are "scrambled" on the tuning dial. That is, if the receiver is tuned to 44 megacycles at one switch position, when the tuning knob is rotated to the next switch position the receiver is tuned, not to the next 6 megacycle channel of 50 megacycles, but to 10 megacycles, for instance. At the next switch position 70 the receiver is tuned to 66 megacycles, etc. 75

The reason for this will be apparent from an inspection of Fig. 4, this being a schematic diagram of the coil 7 and contact points 13 looking from the back side of the coil 7 towards the tuning knob. The figures adjacent to the contact points 13 show the frequency in megacycles to which the receiver is tuned. As shown in Figs. 2 and 4, the leads 15 are brought from the taps on the coil 7 to the nearest switch contact point 10 to keep the leads short. The tap for the 50-megacycle band is three switch contact points away from the tap for 44 megacycles. The contact points on each side of the one opposite the 44-megacycle tap are opposite the taps for 78 megacycles and 102 megacycles. Thus, the television bands are not tuned in regular sequence but this fact is of small importance compared with the advantage of avoiding any long leads between the switch contact points and the taps on the coils.

It may be noted that in the specific example described, the receiver is adjusted to be tuned for reception of both video side bands and both audio side bands, the megacycle markings in Fig. 4 representing the carrier wave frequencies of the incoming audio or sound signals accompanying the picture.

As shown in Fig. 5, the trimmer condenser 44 may be omitted and replaced by a magnetic core 31 for tuning the oscillator coil 37. Rotation of the knob 17 (Fig. 2) causes the core 31 to move in or out to give a fine tuning of the oscillator. The core 31 may be of magnetite manufactured in accordance with the teachings of application Serial No. 56,993, filed December 31, 1935, in the name of R. L. Harvey and assigned to the Radio Corporation of America.

It may be noted that my selector may be made tunable over the entire frequency range of from 44 megacycles to 108 megacycles for the reception of audio signals by making the width of the radio frequency pass band at each tap or switch position equal to the frequency between tap positions, and by making the oscillator tuning range on each tap cover this pass band. The oscillator tuning range may easily be designed to cover the entire pass band as the trimmer condenser 44 is rotated or, in the case of Fig. 5, as the magnetite plug 31 is moved with respect to the oscillator coil.

It will be understood that my variable band pass filter may be utilized for coupling two amplifier tubes or for coupling an amplifier tube and a detector as well as for coupling an antenna to the input tube of the receiver.

In Fig. 1, the values of certain elements have been indicated in micromicrofarads and in ohms by ways of example. The values used for different units obviously depend upon the type tubes employed, size of coils, etc.

As shown in Fig. 6, the circuits 2 and 3 may be coupled by a condenser 90, which provides parallel capacitive coupling, instead of by the condenser 12 (Fig. 1). In Figs. 1 and 6 like parts are indicated by the same reference numerals. While series capacitive coupling is preferred, the circuits shown in Figs. 1 and 6 have the common characteristic that the pass band width tends to stay constant over the entire tuning range because of the effect of the distributed capacity.

I claim as my invention:

1. A station selector device for high frequency receivers designed to receive signals from a selected one of a plurality of transmitting stations, said device comprising a tuned primary

circuit and a tuned secondary circuit, said circuits being coupled by means of a coupling condenser common to said circuits, each of said circuits including a tapped inductance coil, said circuits being so tuned and coupled as to form a band pass filter having a pass range which is narrow enough to provide selectivity between adjacent frequency bands utilized by said transmitting stations, and means including switching means associated with the taps on said coils for varying their inductance simultaneously in such manner that said pass range may be shifted to receive signals from a selected one of said stations, said inductance coils having distributed capacity of such value that said pass range remains approximately constant as said selector device is tuned over its tuning range.

2. A station selector device for high frequency receivers designed to receive signals from a selected one of a plurality of transmitting stations, said device comprising a tuned primary circuit and a tuned secondary circuit, said circuits being coupled by means of a coupling condenser common to said circuits, each of said circuits including a tapped inductance coil, said circuits being so tuned and coupled as to form a band pass filter having a pass range which is narrow enough to provide selectivity between adjacent frequency bands utilized by said transmitting stations, means including switching means associated with the taps on said coils for varying their inductance simultaneously in such manner that said pass range may be shifted to receive signals from a selected one of said stations, and a resistor connected effectively across the tapped section of one of said coils whereby the damping effect of said resistor decreases as said selector device is tuned to a higher frequency.

3. A station selecting device for high frequency receivers designed to receive signals from a selected one of a plurality of transmitting stations, said device comprising a primary circuit including an inductance coil, a tuning capacity and a coupling condenser all connected in series, a secondary circuit including an inductance coil, a tuning capacity and said coupling condenser all connected in series, said circuits being so tuned and coupled as to form a band pass filter having a pass band narrow enough to provide selectivity between adjacent frequency bands utilized by said transmitting sections, each of said coils having a plurality of tapped points and switching means for connecting to said points, and means for simultaneously varying the inductance of said coils to shift said pass band by actuating said switching means.

4. A station selector device for high frequency receivers for the reception of signals from a selected one of a plurality of transmitting stations, said device comprising a tuned primary circuit including an inductance coil and a tuned secondary circuit including an inductance coil, said circuits being coupled by means of a coupling condenser common to said circuits, said circuits being so tuned and coupled as to form a band pass filter having a pass range which is narrow enough to give selectivity between adjacent frequency bands utilized by said stations, and switching means for simultaneously shorting a portion of each of said coils and thereby varying the inductance of said circuits in such manner that said pass range is shifted to receive signals from a selected one of said stations, said inductance coils having distributed capacity of such value that said pass range remains approximately con-

stant as said selector device is tuned over its tuning range.

5. A station selector device for high frequency receivers, said device comprising a gang switch of the type having a rotatable switch shaft, switch arms mounted on said shaft and rotatable therewith, said switch arms being spaced longitudinally along said shaft, a plurality of disc or plate elements each having a plurality of switch contact points mounted thereon and insulated from each other for cooperating with said switch arms, each of said disc elements being mounted adjacent to one of said switch arms, terminals for said contact points mounted on each of said disc elements and arranged substantially in a circle, a plurality of inductance coils supported in coaxial relation to said gang switch, each of said coils being positioned adjacent to the terminals on one of said disc elements, each coil having tapped points thereon connected to adjacent terminals, and capacity means connected across said coils whereby a plurality of tunable circuits are formed which may be tuned to different frequencies by rotating said switch shaft.

25 6. A station selector device for high frequency receivers, said device comprising a gang switch of the type having a rotatable switch shaft, switch arms mounted on said shaft and rotatable therewith, said switch arms being spaced longitudinally along said shaft, a plurality of disc or plate elements each having a plurality of switch contact points mounted thereon and insulated from each other for cooperating with said switch arms, each of said disc elements being mounted adjacent to one of said switch arms, terminals for said contact points mounted on each of said disc elements and arranged substantially in a circle of a certain diameter, and a plurality of inductance coils supported in coaxial relation to said gang switch, each of said coils having an external diameter less than said certain diameter and being positioned adjacent to the terminals on one of said disc elements, each coil having tapped points thereon, each of which is connected to the nearest one of said terminals by a short lead.

7. The invention according to claim 6 characterized in that said leads are sufficiently rigid to act as supports for said coils.

8. A station selector for a high frequency superheterodyne receiver, said selector comprising a gang switch having a rotatable switch shaft and having at least three switches spaced longitudinally along said axis, each of said switches comprising a switch arm attached to said shaft and a

plurality of contact points mounted in a circle substantially in the plane of said arm and in cooperating relation therewith, at least three inductance coils, each of said coils being mounted adjacent to one of said switches and in coaxial relation thereto, a tuned primary circuit including one of said coils, a tuned secondary circuit including another of said coils, a coupling condenser common to said primary and secondary circuits, said circuits being so coupled and tuned as to form a band pass filter having a certain pass range, said one coil and said other coil having tapped points each connected to the nearest switch contact point by a short lead whereby said pass range may be shifted by rotating said switch shaft, and an oscillator having a tuned circuit including a third one of said coils, said third coil having tapped points each connected to the nearest contact point of the adjacent switch whereby the oscillator frequency is changed simultaneously with the change in said pass range as said shaft is rotated.

9. The invention according to claim 8 characterized in that said oscillator comprises a vacuum tube having a plate circuit and a grid circuit, said oscillator tuned circuit being included in said plate circuit, a grid coil in said grid circuit, said grid coil being inductively coupled to said oscillator tuned circuit and being so located that it is located within the short-circuited turns of said third coil when said selector is tuned to the highest frequency in its tuning range.

10. A station selector device for high frequency receivers for receiving signals from a selected one of a plurality of transmitting stations, said device comprising a tuned primary circuit and a tuned secondary circuit, said circuits being coupled by means of a condenser common thereto, each of said circuits including a tapped inductance coil, said circuits being so tuned and coupled as to form a band pass filter having a pass range which is narrow enough to provide selectivity between adjacent frequency bands utilized by said stations, switching means including switch contact points connected to said tapped points for shorting out portions of said coils whereby said pass range may be changed, a coupling coil for coupling a transmission line to said primary coil, said coupling coil being located partly within and partly outside the short circuited turns of said primary coil when said device is tuned to the highest frequency in its tuning range.

ALFRED H. TURNER.
